Summer King. 9535X
machine for working off the ends, & smoothing ends.

The schedule referred to in these Letters Patent and making part of the same containing a description in the words of this said Summer King himself of his improvement in the machine for working off the ends and smoothing ends. Dr. G.

To all to whom these Presents shall come,
Be it known, that J. Summer King, of Suffield in the county of Hartford and State of Connecticut, have invented a new and useful improvement in working off the ends, and smoothing ends of all descriptions, and that the following is a full and exact description of the construction and operation of this said machine as invented or improved by me, and

It consists of a revolving grapple tub, or any other grapple to secure the ends, to be placed upon an arbor, the arbor to have two pulleys on it, one right for a band to pass round for the purpose of driving the tub, and the other loose to let the band on to which the tub is to be stopped. The arbor to have a plate or collar on one end of sufficient diameter to admit of a bolt being fastened on to it, with bolts passing through the collar and bottom of the tub.

The tub to have one end of the arbor fastened to the bottom, the other end loose, so as to expand so as admit one end of the cable that is to be worked or turned into it, and make fast by driving on a ~~lock~~ When the cable is made fast in the tub it revolves, and tools are held on to work it off consisting of a bowline, a stock, hawls, a cross and a plane. The arbor to be directed on a frame, or floor of the building and to be propelled by any power.

What I claim as my invention or improvement is the revolving grapple tub, that secures the ends.

John. S. King
Albert King.
